UNITED STATES PATENT OFFICE

WILLIAM D. KYLE, OF MILWAUKEE, WISCONSIN, ASSIGNOR, BY MESNE ASSIGNMENTS, TO LINE MATERIAL COMPANY, OF SOUTH MILWAUKEE, WISCONSIN, A CORPORATION OF DELAWARE

FUSE

Application filed April 2, 1928. Serial No. 266,681.

This invention relates to certain new and useful improvements in fuses and refers more particularly to the type known as expulsion fuses.

5 It is desirable that a single fuse structure be equally applicable for use with either low or high voltages having a range of at least 2300 to 6600 volts; but inasmuch as higher voltages require a very rapid volatilization 10 of the fuse element to insure rupturing of the circuit before any damage can be done thereto or to the fuse itself and as the relatively lower voltages require a slower speed of volatilization of the fuse element to allow 15 practically all the element to burn away and thus prevent leakage, it has been extremely difficult in the past to so balance the design and construction of a fuse structure to function satisfactorily both at high and 20 low voltages. It is, therefore, an object of this invention to provide a fuse of the character described which is so constructed as to be equally adaptable for use with either high or low voltages.

25 Another object of this invention resides in the provision of a fuse employing two independent tubes and a fuse link of substantially U-shape.

A further object of this invention resides 30 in the provision of a fuse of the character described, having two independent tubes of different inside diameters within which the ends of a U-shaped fuse link are positioned.

35 And a still further object of this invention resides in the provision of a fuse of the character described having a pair of tubes in which the ends of a U-shaped link are positioned to be connected at their outer ends with contacts carried by each tube, the contacts having an insulating barrier positioned 40 therebetween to increase the creepage distance.

With the above and other objects in view which will appear as the description proceeds, my invention resides in the novel construction, combination and arrangement of parts substantially as hereinafter described and more particularly defined by the appended claims, it being understood that such 45 changes in the precise embodiment of the

herein disclosed invention may be made as come within the scope of the claims.

In the accompanying drawing I have illustrated one complete example of the physical embodiment of my invention constructed according to the best mode I have so far devised for the practical application of the principles thereof, and in which:

55 Figure 1 is a front view of a fuse structure embodying my invention with the housing cover removed, and parts thereof being broken away and in section to more clearly illustrate details of construction, and

60 Figure 2 is a cross sectional view taken on the plane of line 2—2 of Figure 1.

65 Referring now more particularly to the accompanying drawing in which like numerals designate like parts, 5 designates a housing preferably formed of porcelain or the like and having sides 6, a top 7 and a back 8; the bottom thereof being open and the front being closed by a cover 9 which is hinged at its lower portion to the housing 5 in any suitable manner (not shown) to swing 70 over the open front of the housing.

75 A barrier 10 is molded integral with the housing and is extended downwardly from the top 7 and outwardly from the back 8, being positioned medially of the sides 6 as illustrated. Positioned at the upper portion 80 of the housing between each side 6 and the barrier 10 are a pair of contact clips 11 which are secured by screws 12 to terminal members 13 suitably mounted in the back 8 of the housing and to which the ends of conductors 14 are electrically connected by means of set 85 screws 15, the conductors 14 passing through apertures in the side walls 6 to connect the fuse with an electrical circuit and the barrier 10 being of sufficient size to prevent 90 creepage from one contact clip to the other.

95 The fuse proper is composed of a tube 16 and a tube 17, the tube 16 is of greater internal and external diameter than the tube 17 and the upper ends thereof have mounted thereon contacts 18 which are adapted to be inserted between the spring contact clips 11 and thereby electrically connected with the conductors and the electrical circuit. Each contact member 18 is provided with an up- 100

wardly extending centrally bored projection 19 which is externally threaded to receive a cap member 20 between the inner end wall of which and the outer end of the projection 19 the ends 21 of a fuse element 22 are adapted to be impinged; the ends being preferably bent as illustrated in Figure 1 to approximately T shape. As is customary in fuse links of this nature, a portion thereof has its cross sectional area reduced as at 23, at which point the initial rupture takes place.

Tubes 16 and 17 are carried by the cover member 9 and are secured thereto by U bolts 24 which embrace the tubes at a medial point and have their ends extended into apertures within the cover member and threaded to receive clamping nuts 25. Suitable cradle members 26 extend from the inner face of the cover member above and below the U bolts 24 to maintain the tubes in their proper position.

When the voltage with which the fuse is to be used is relatively low, the operator places the fuse as shown in the drawing with reduced section of the link within the tube of larger diameter so that upon an overload the volatilization of the link is sufficiently slow to insure enough of the link being burnt away to prevent the possibility of leakage, and when it is desired to utilize the fuse with voltages of relatively higher value it is only necessary to reverse the position of the link so that the initial rupture occurs within the tube of smaller inside diameter to insure rapid volatilization of the fuse link and to rupture the circuit before any damage can be done to either the equipment or fuse.

Inasmuch as each tube is of sufficient length to satisfactorily rupture the particular voltage for which it is intended, the other tube increases the protection and safety factor and prevents any possibility of the arc holding on.

What I claim as my invention is:

1. In a fuse structure of the character described, a tube, a second tube of smaller inside diameter, contacts carried by each tube, and a fuse link having one end connected with the contact of one tube and its other end connected with the contact of the other tube.

2. In a fuse of the character described, a tube adapted for use with relatively low voltages, a second tube having different characteristics and adapted for use with relatively high voltage, contacts carried by each tube, an insulating barrier between the contacts, a fuse element having a reduced cross sectional area adjacent one end thereof, and means connecting one end of the element with each contact, the reduced cross sectional area of the element being placed within the tube corresponding to the voltage with which it is to be used.

3. In a fuse structure of the character described, a housing member, an insulating bar-

rier positioned within the housing member, contact clips carried by the housing, one on each side of the insulating barrier, a pair of tubes having different inside diameters, contacts carried one by each tube, a fuse element electrically connecting the contacts, and means whereby the contacts of the tubes may be simultaneously connected with the contact clips to electrically bridge the same through the fuse element.

4. In a fuse structure of the character described, a tube adapted for use with relatively low voltages, a second tube of different characteristics and adapted for use with relatively high voltages, contacts carried by the tubes, and a fuse element having one end portion passed into one tube and connected with the contact thereof and its other end portion passed into the other tube and connected with the contact thereof.

In testimony whereof I have hereunto affixed my signature.

WILLIAM D. KYLE.
